United States Patent Office.

AUGUST STEINBÖK, OF NEW YORK, N. Y.

Letters Patent No. 96,163, dated October 26, 1869.

IMPROVEMENT IN MATCH-SAFES.

The Schedule referred to in these Letters Patent and making part of the same.

To all whom it may concern:

Be it known that I, AUGUST STEINBÖK, of New York, in the county of New York, and State of New York, have invented a new and improved Match-Safe; and I do hereby declare that the following is a full, clear, and exact description thereof, which will enable others skilled in the art to make and use the same, reference being had to the accompanying drawings, forming part of this specification, in which—

Figure 1 represents a longitudinal sectional view of my improved match-safe.

Figure 2 is a plan or top view of the same.

Similar letters of reference indicate corresponding parts.

This invention relates to improvements in match-safes; and

It consists in the combination of the self-igniting wick with the closed case, provided with a sliding cover and an adjustable candle-holder, as will be hereinafter more fully described.

A, in the drawing, represents a box or case, made of sheet-metal, or other suitable material, of suitable size and form.

In it is arranged a wick, B, which can, by a ratchet-wheel, a, or otherwise, be fed up or down, at will.

The box is provided with an opening, b, in its top or side, and the wick can, by means of the feeding-apparatus, be caused to project through said opening, as in fig. 1.

The wick has been prepared by being dipped in a

solution of saltpetre, and, after being dry, in another solution of phosphorus, in bisulphuret of carbon, so that it has thereby been made self-igniting.

It may be treated with other suitable chemicals, and I do not confine myself to the use of the preparation specified.

The end of the wick will, when forced out through the opening b, be spontaneously ignited, without the use of friction, by simple contact with the air. When not to be used, the wick is withdrawn into the box, and the aperture b is closed by a slide, cover, or valve, C.

The box may contain another compartment, D, in which a taper or candle-holder, E, may be arranged. This holder can be arranged sliding, so that the candle can be forced out, as in fig. 1, to stand so near to the wick that it will be ignited by the same. The wick can be drawn in, and the cover or slide C closed, as soon as the candle is thus lighted.

Having thus described my invention,

I claim as new, and desire to secure by Letters Patent—

The self-igniting wick B, in combination with the closed case A, having the sliding cover C, ratchet a, and adjustable candle-holder E, all arranged as described, for the purpose specified.

AUGUST STEINBÖK.
